UNITED STATES PATENT OFFICE

105,948

DESIGN FOR A PROJECTOR

Maurice H. Goldberg, Chicago, Ill.

Application May 29, 1937, Serial No. 69,625

Term of patent 3½ years

To all whom it may concern:

Be it known that I, Maurice H. Goldberg, a citizen of the United States, residing at Chicago, county of Cook, and State of Illinois, have invented a new, original, and ornamental Design for a Projector, of which the following is a specification, reference being had to the accompanying drawings, forming a part thereof.

On the drawings,

Figure 1 is a side elevation of the projector showing my new design, the opposite side presenting substantially the same appearance as the side shown, and

Fig. 2 is a top plan view thereof.

I claim:

The ornamental design for a projector as shown and described.

MAURICE H. GOLDBERG.
